By Edward H. Riley his Atty

UNITED STATES PATENT OFFICE.

GEORGE A. REYNOLDS, OF UTICA, NEW YORK.

LAST.

SPECIFICATION forming part of Letters Patent No. 293,913, dated February 19, 1884.

Application filed December 20, 1883. (No model.)

To all whom it may concern:
Be it known that I, GEORGE A. REYNOLDS, of the city of Utica, Oneida county, in the State of New York, a citizen of the United States, have invented a new and useful Improvement in Lasts; and I do hereby declare the following to be a full, clear, and exact description of the same, reference being had to the accompanying drawings, and to the letters and figures marked thereon—

My invention and improvement relates to that class of mechanism consisting of a metallic last constructed in two parts, and the manner and method of attaching the same together, and of expanding and depressing the upper surface thereof.

A patent was granted to Edward S. Kings-
ton for a metallic last constructed in two parts,
and is No. 273,108, of which I am now the sole
owner by assignments from the patentee.

My invention relates to an improvement in
attaching the two portions or parts of the last
together at the toe, and in the method of ex-
panding the upper portion and holding the
same rigid when in use, and of lowering the
same when the last is to be withdrawn from
the shoe or boot.

In the accompanying drawings, Figure 1 re-
presents a side elevation of the last. Fig. 2 re-
presents a section of the last with my improve-
ments attached. Fig. 3 represents the rear
elevation of my improvement. Fig. 4 repre-
sents the rear elevation of a movable support.
Fig. 5 represents a top view of the same. Fig.
6 represents a side view of the same. Fig. 7
represents a top view of a section of my last,
representing the method of attaching the upper
section to the lower section. Fig. 8 repre-
sents an end view of the lower section of the
last.

A represents the lower section of my metal-
lic last. B represents the upper section of the
same. Dotted lines (represented by C) repre-
sent the upper section of the last when ex-
panded.

D represents the metallic posts or guides at-
tached to the lower sections of the last by screw,
bolt, or rivet, or may be cast in connection
with the same, and are from a quarter to a
half an inch apart, according to the wishes of
the manufacturer, and about two inches in
length. The upper portions of the posts are

attached by rivet or screw, or may be formed
by casting the same together, and are adapted
to receive between them the support E. 55

D' represents a metallic catch. The upper
portion is attached to B by rivets or bolts, or
may be cast with the same. The lower end is
provided with a projecting catch adapted to
move between posts D. The catch is adapted 60
to strike the upper connection of post D, as
indicated in Fig. 3.

E represents a movable support, and is
formed of malleable iron, brass, or any other
suitable metal, and is of sufficient width to 65
loosely fit between posts D, upon the front of
which are cross-bars extending from a quar-
ter to a half an inch beyond the surface of the
same, as indicated in Fig. 4, and are adapted
to fit against posts D, as indicated in Fig. 2. 70
Upon the rear is an extension-arm substan-
tially at right angles and adapted to fit be-
tween posts D, and when inserted the project-
ing end is turned at right angles, as indicated
in Fig. 3, and is designed to regulate the for- 75
ward movement of the support and to keep
the same in place.

e represents the projections attached to the
support E.

e' represents the rear projection or stop with 80
a right-angled bend adapted to hold the stop
or support and to prevent the same from slip-
ping out of place, and so constructed that when
the toe of the last is turned downward and the
top surface, B, is extended, the support will 85
drop forward and allow A and B to be com-
pressed, so that the last can be removed from
the shoe; and when in use the support can be
put in place by turning the heel of the last
downward and extending A and B, and forms 90
a solid metallic support to the two surfaces of
the last.

F represents a projecting surface of the up-
per portion of the last, and is dovetailed into
the lower section. 95

F' represents the dovetailed slot on the toe
of the lower section of the last, and is designed
to receive the dovetailed flange on the upper
surface of the last and to hold the same loosely
to allow the vertical motion of B, as indi- 100
cated in Fig. 1, and to hold the same from
slipping out of place when in use, and adapted
at the same time to give a smooth and even
surface to the toe of the last.

Similar letters refer to similar parts throughout.

By the use of my improvement the spring can be entirely omitted and the joint at the 5 toe dispensed with.

What I claim as new, and desire to secure by Letters Patent, is—

1. In an adjustable metallic last, the parts A and B, in combination with posts D and D', 10 as described.
2. In an adjustable metallic last, parts A

and B, provided with posts D and D', and support E, provided with extensions e and e', as described.

3. In an adjustable metallic shell-last, parts 15 A and B, provided with tongue F and groove F', posts D and D', and support E, provided with extensions e and e', as described.

GEORGE A. REYNOLDS.
